[57] CLAIM

The ornamental design for a curler/styler, as shown and described.

DESCRIPTION

FIG. 1 is a perspective view of a curler/styler showing our new design;

FIG. 2 is a top plan view thereof;

FIG. 3 is a side elevational view of the side opposite the side shown in FIG. 1;

FIG. 4 is a bottom plan view thereof;

FIG. 5 is a front end elevational view thereof; and

FIG. 6 is a rear end elevational view thereof.
